UNITED STATES PATENT OFFICE.

HENRY C. FRANK, OF NEW YORK, N. Y.

CLASP.

SPECIFICATION forming part of Letters Patent No. 731,103, dated June 16, 1903.

Application filed March 21, 1903. Serial No. 148,838. (No model.)

To all whom it may concern:

Be it known that I, HENRY C. FRANK, a citizen of the United States, and a resident of the borough of Manhattan, in the city and State 5 of New York, have invented a new and useful Improvement in Clasps, of which the following is a specification.

My invention relates to an improvement in clasps, and has for its principal object to provide a clasp which will hold a garment without slipping and yet at the same time reduce the liability of tearing the garment to a minimum.

A further object is to provide a clasp comprising two members having their jaws each provided with a toothed portion and a plain portion, the toothed portions being fitted to lap past the plain portions when the clasp is closed.

A practical embodiment of my invention is represented in the accompanying drawings, in which—

Figure 1 represents my improved clasp in end elevation forming part of a cuff-holder. Fig. 2 is a top plan view of the same. Fig. 3 is a side view of the clasp in its closed position. Fig. 4 is a view similar to Fig. 1, showing the clasp open; and Fig. 5 is a side view of the clasp in its open position.

The cuff-holder in connection with which my improved clasp is shown comprises a shank 1 and a suitable hook 2 for engaging the cuffs.

The clasp comprises two members 3 and 4, hinged together by means of a pin or pintle 5 passing through side lugs or ears 6 and 7 of the members 3 and 4. A spring 8, coiled around the pintle 5, has its ends 9 and 10 engaged with the members 3 and 4, tending to hold their jaws 11 and 12 together.

The jaw 11 of the member 3 of the clasp is provided with a toothed portion 13 and a plain portion 14. The jaw 12 of the member 4 of the clasp is also provided with a toothed portion 15 and a plain portion 16. The toothed

and plain portions of one jaw are fitted to lap past the plain and toothed portions, respectively, of the other jaw. In the accompany-

ing drawings I have shown the toothed portions of both of the jaws as being fitted to overlap the plain portions of the jaws when 50 the clasp is closed by bending the plain portions 14 and 16 of the jaws inwardly and the toothed portions 13 and 15 of the jaws outwardly.

A clasp constructed as herein set forth may 55 be engaged with thin goods without tearing them. This is particularly so where the clasp is used in connection with a cuff-holder where it is caused to grasp a shirt-sleeve, so that the strain upon the jaws comes in a lateral 60 direction rather than longitudinally of the clasp.

I am aware that clasps have been made in which the jaws were made plain; but these clasps are objectionable, for the reason that 65 they will not hold the garment firmly, especially when used in connection with thin material. Furthermore, the objection to clasps provided entirely with toothed jaws lies in the fact that when used in connection with 70 thin goods, especially, the thin goods are very easily torn between the overlapping or even intersecting toothed edges of the jaws. It is these objectionable features which I have overcome in the construction of clasp herein 75 described, in which the plain portion of one jaw laps past the toothed portion of the other jaw.

What I claim is—

A clasp comprising two members having 80 jaws, each jaw being provided with a toothed portion and a plain portion, the toothed portions being bent outwardly and the plain portions being bent inwardly whereby the toothed portions are fitted to overlap the plain 85 portions when the clasp is closed.

In testimony that I claim the foregoing as my invention I have signed my name, in presence of two witnesses, this 19th day of March, 1903.

HENRY C. FRANK.
